(57) **CLAIM**

The ornamental design for a light generating apparatus, as shown and described.

DESCRIPTION

FIG. 1 is a left side view of a first embodiment of my new design wherein the light generating apparatus is configured as a desk lamp;

FIG. 2 is a right side view thereof;

FIG. 3 is a top view thereof;

FIG. 5 is a back view thereof;

FIG. 6 is a front view thereof;

FIG. 7 is a left front perspective view thereof;

FIG. 8 is a back perspective view thereof;

FIG. 9 is a left side view thereof, showing my new design in a first alternate position;

FIG. 10 is a right side view thereof;

FIG. 11 is a top view thereof;

FIG. 12 is a bottom view thereof;

FIG. 13 is a back view thereof;

FIG. 14 is a front view thereof;

FIG. 15 is a left front perspective view thereof;

FIG. 16 is a back perspective view thereof;

FIG. 17 is a left side view thereof, showing my new design in a second alternate position;

FIG. 18 is a right side view thereof;

FIG. 19 is a top view thereof;

FIG. 20 is a bottom view thereof;

FIG. 21 is a back view thereof;

FIG. 22 is a front view thereof;

FIG. 23 is a left front perspective view thereof;

FIG. 24 is a back perspective view thereof;

FIG. 25 is a left side view of a second embodiment of my new design wherein the light generating apparatus is configured as a floor lamp;

FIG. 26 is a right side view thereof;

FIG. 27 is a top view thereof;

FIG. 28 is a bottom view thereof;

FIG. 29 is a back view thereof;

FIG. 30 is a front view thereof; and,

FIG. 31 is a back perspective view thereof.
